UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

DOOR OPERATING AND LOCKING DEVICE.

Application filed December 8, 1923. Serial No. 679,290.

To all whom it may concern:

Be it known that I, STACY B. HASELTINE, a citizen of the United States, residing at Chicago, in the county of Cook and State of Illinois, have invented a certain new and useful Improvement in Door Operating and Locking Devices, of which the following is a full, clear, concise, and exact description, reference being had to the accompanying drawings, forming a part of this specification.

This invention relates to improvements in door operating and locking device.

One object of the invention is to provide an exceedingly simple and inexpensive device, which is applied to doors of the sliding type, having effective means for drawing the door closed and also operative to start the opening of the same.

Another object of the invention is to provide means for locking the door in either closed or partly opened position.

A still further object of this invention is to provide a device of the character indicated for operating sliding doors to either force the door open or pull the same closed, including toggle lever acting mechanism which also serves to hold the door in either a closed or partly opened position, together with means for locking the mechanism to retain the door in either of said positions.

Other objects and advantages of the invention will more clearly appear from the description and claims hereinafter following.

In the drawing, forming a part of this specification, Figure 1 is a side elevation of a portion of a box car, showing a portion of the sliding door thereof, with my improvements in connection therewith. Figure 2 is a horizontal, sectional view corresponding substantially to the line 2—2 of Figure 1. Figure 3 is a view similar to Figure 1, illustrating the door in partly opened position and showing my improved device in the position assumed prior to the closing operation thereof, and further showing, in dotted lines, the position of the parts when the door is locked in partly opened position. And Figure 4 is a vertical, sectional view corresponding substantially to the line 4—4 of Figure 1, the same being on a somewhat enlarged scale.

In said drawing, 10 denotes the sliding

side door of a railway box car and 11 the side wall thereof. One of the door posts is indicated at 12, the same being cut away at its outer side to provide a door stop 13 against which the front edge of the door is adapted to bear when the same is in fully closed position.

The improved door operating and locking device, as shown, comprises broadly, a bracket A; a strap B; a link C; an operating lever D; a latch member E; a lever support F; and a wear plate G.

The lever D is in the form of an elongated flat bar of rectangular cross section, slightly tapered toward the handle and, thereby providing a hand grip portion 14 of convenient size at one end thereof, the hand grip being inwardly offset as clearly shown in Figure 3. At the opposite end, on the side thereof adjacent the car wall, the lever D is provided with a laterally projecting, cylindrical fulcrum member 15, the same being preferably formed integral with the lever. The latter is also provided with a pair of lugs 16 and 17 on one edge thereof, the lugs being adapted to extend upwardly when the lever is disposed in horizontal position as clearly shown in Figure 1. The lug 16 is relatively small, is located adjacent the fulcrum end of the lever, and is extended laterally to overhang the link 18 and engage with the upper edge of the latter to prevent sagging of the parts when the lever and link are in dotted line position in Figure 3. The lug 17 which is considerably larger than the lug 16 is disposed adjacent the hand grip portion 14, being spaced an appreciable distance inwardly from the end of the lever.

The link C, which, in the form of a flat bar, is pivotally connected at one end to the lever D, at a point spaced inwardly from the fulcrum thereof by means of a rivet member 18. The opposite end of the link C is pivotally connected to one end of the supporting strap B by a rivet member 19. The strap B is horizontally disposed and bears flatly against the outer surface of the door, being fixed to the latter by bolts 20 or any other suitable form of securing devices. Upon reference to the drawing, it will be seen that the pivots of the link and lever are so disposed that the lever swings in a plane parallel to the side of the car, and that

the lever may assume a pendant position under the influence of gravity, as clearly shown in dotted lines in Figure 1.

The bracket A is in the form of a plate applied to the door stop 13 and the adjacent portion of the side wall of the car, being secured thereto by bolts 21-21 or any other suitable fastening devices. That portion of the plate applied to the door stop is outwardly offset with reference to the main body portion of the plate as indicated at 22 in Figure 2 and is set into the stop so as to have the outer surface thereof flush with the outer face of the stop. Along its lower edge the plate is provided with an outstanding horizontally disposed flange 23 extending from the offset portion to the opposite end of the plate, the front end of the flange being substantially in alinement with the outer face of the door stop and door. The offset portion 22 of the plate is indented to provide a pocket as indicated at 24 adapted to accommodate the fulcrum member 15 of the lever D. The door stop 13 is correspondingly recessed to receive the indented portion of the plate. At the bottom of the pocket 24 an outstanding lug 25 is provided having an upwardly inclined front face 26 on which the fulcrum member 15 of the lever is adapted to ride. At its rear side, the lug has a vertically disposed abutment face behind which the fulcrum member is adapted to engage. The pocket 24 is also provided with a vertically disposed end wall 27 adapted to form an abutment for the fulcrum member. As shown, the lug 25 is spaced from the end wall 27 a sufficient distance to accommodate the fulcrum member therebetween. Formed integral with the plate is a hood, comprising a longitudinally extending, vertically disposed side wall 28 and a longitudinally extending top wall 29. The side wall 28 is spaced outwardly from the outer edge of the flange 23 and the outer face of the door stop 13 a sufficient distance to permit the lever D to swing therebetween and a portion thereof is offset as shown in Figure 2 to accommodate the link C. The lower edge of the wall is preferably beveled at the inner side as indicated at 30 to aid in properly guiding the lever behind the wall. Formed integral with the bottom edge of the wall 28 at the rear end of the hood is a laterally projecting, horizontally disposed ear 31 provided with an opening for a purpose hereinafter described. Adjacent the rear end of the hood, the top wall 29 is provided with an opening 32 adapted to receive the lug 17 in one of the positions of the lever D.

60 The latch member E comprises a vertically disposed bearing member 33 and a horizontally disposed arm 34 extending therefrom. The bearing member 33 is disposed between the upper wall 29 of the hood and the flange 23 having its lower end supported by the lat-

ter. The bearing member 33 is pivotally mounted to swing about a vertical axis on a bolt 35 extending therethrough, through the wall 29 and flange 23. The upper portion of the bearing member 33 is of cylindrical form and bears on the curved surface 36 of the wall of a downwardly opening pocket 37 into which it extends. The arm 34 is adapted to be swung into position at right angles to the side wall of the car and under the ear 31 to support the lever D when in horizontal position, as clearly shown in Figures 2 and 4. The free end of the arm is provided with an opening 38 which is adapted to register with the opening in the ear 31 when the arm is swung into position under the ear. The registering openings in the arm and ear are adapted to receive the usual car seal or any other locking member in a well known manner. A vertically disposed rib 39 outstanding from the plate of the bracket A acts as a limiting stop for the arm to assure registration of the seal receiving openings.

As clearly shown in the drawings, when the arm 34 is in the position just described, supporting the lever D, the latter is confined within the hood of the bracket A and retained in position by the walls 28 and 29 thereof, the offset portion of the plate and the wall of the pocket 36. It will be evident that the fulcrum member 15 is thus prevented from being disengaged from behind the lug 25.

The car door is cut away at the outer side adjacent the front edge as indicated at 40 to accommodate the fulcrum member 15 when the lever and link are in the pendant position, and the wear plate G which is applied to the outer surface of the door and secured thereto by screws is provided with a similar opening registering with the opening in the door, the edges of the plate along the opening therein providing wear surfaces protecting the walls of the opening 40.

The supporting member F is pivotally mounted on the outer side of the door by a bolt 41 extending through the upper end thereof and is provided with a socket 42 adapted to receive the extremity of the handle 14 of the lever to support the lever in an inclined position with the fulcrum member 15 thereof so disposed that it will engage the inclined face 26 of the lug 25 when the door is moved toward the stop. The position of the bolt 41 is such that the center of gravity of the support F is disposed to one side of the pivot point thereof when the end of the lever is engaged within the socket 42 so that the support will be held in engaging position with the lever under the influence of gravity.

Assuming that the parts are in the full line position shown in Figure 1, the lever being disposed horizontally with the fulcrum member thereof between the lug 25

and the abutment wall 27, when it is desired to open the door, the following sequence of operations are performed. The lead seal being first broken and removed, the latch member E is swung to the right, as seen in Figure 1, through an arc of 90°, thereby freeing the lever D from within the pocket defined by the hood. The lever is then swung downwardly in a contra-clockwise direction turning on its fulcrum member 15 which at this time bears on the wall 27 and the bottom wall of the pocket 24, forcing the door open through the medium of the connecting link C, the lever and the link acting in the manner of a toggle mechanism. The swinging movement of the lever in the described direction is continued until the desired amount of door opening is obtained, whereupon the fulcrum of the lever is manually disengaged from behind the lug 25 and the lever and link permitted to drop to the dotted line position shown in Figure 1.

When it is desired to close the door, the latter is moved to a position as near the stop 13 as can be conveniently done by the operator without the use of tools. Such a position is indicated in full lines in Figure 3. During the time that the door is moved to this position, the lever D may be supported by the member F as shown, to properly guide the fulcrum member of the lever into engagement with the inclined surface of the lug 25. However, it is not necessary that the lever be so supported while pushing the door to the position shown in Figure 3, but the same may be allowed to hang pendant and then manually engaged with the lug 25 when the door has reached a position shown in Figure 3. Assuming that the lever is supported as shown in Figure 3, as the door is pushed toward the stop, the fulcrum member 15 will ride upon the inclined surface 26 of the lug 25, finally passing beyond the same and dropping behind the lug and will be confined between the same and the wall 27 of the pocket 24. To force the door to closed position, the lever D is swung in a clockwise direction, the support F being first disengaged from the handle. It will be evident that as the lever is swung to a horizontal position within the hood of the bracket A, the door will be positively pulled shut through the medium of the connecting link C, the parts acting in the manner of a toggle mechanism as hereinbefore pointed out. To lock the door in position, the latch E is swung into engagement with the stop 39, thereby supporting the lever D and preventing disengagement of the fulcrum member 15 from between the lug 25 and the wall 27. The usual seal is then applied through the alined openings of the arm 34 and ear 31.

To lock the door in the partly opened position as shown in Figure 3, the lever D

and link C are raised to the dotted line position and the lug 17 of the lever engaged within the recess 32 in the upper wall of the hood of the bracket. The latch E is then swung into position to aline the opening thereof with the opening of the ear 31 and the usual car seal applied. It will be evident that the arm 34 of the latch E supports the lever D when in the dotted line position in a manner similar to that hereinbefore described, the lug on the lever being thereby retained within the recess 32, and the link and lever prevented from sagging at their pivotal connection by the lug 16 which engages the top edge of the link inwardly of its pivotal connection with the lever.

With the arrangement I have provided, a strong pulling force can be easily obtained to force the door to closed position even though the door may be badly sagged or distorted. It will also be evident that due to the toggle arrangement, the maximum amount of force is applied during the final closing and initial opening movement of the door.

I have herein shown and described the plate A as secured to the door post and stop, and the other parts of the device on the sliding door. It will be understood, however, that the position of the parts may be inter-changed without departing from the spirit of the invention and I contemplate all changes and modifications that come within the scope of the claims appended hereto.

I claim:

1. In an operating and locking mechanism for a sliding door, the combination with an abutment member; of toggle means adapted to be detachably connected with said abutment member for operating the door, said means including a hand operated lever carried thereby; and means including a horizontally disposed latch arm for locking said lever to said abutment to hold the door in closed position.

2. In an operating and locking mechanism for a sliding door, the combination with an abutment member; of toggle means adapted to be detachably connected with said abutment for operating the door, said means including an operating lever movable in a vertical plane; and cooperating means on said lever and abutment for locking the door in two different positions.

3. In an operating mechanism for a sliding door member associated with a frame member, the combination with an abutment element fixed to one of said members; of a link pivoted on the other member and adapted to swing in a plane parallel to the side of the car; an operating lever hinged to the link for movement in a plane parallel thereto, said operating lever having means

thereon for detachably connecting the same to said abutment element.

4. In an operating mechanism for a sliding door associated with a frame member having a door opening therein, the combination with a bracket fixed to one of said members, said bracket having abutment means thereon; of toggle means bodily swiveled on the other member and adapted to assume a pendant position under the influence of gravity, said means including a link and a lever confined to movement in parallel planes; and a fulcrum element on said lever adapted to be detachably engaged with the abutment means on said bracket, whereby upon operation of said lever in one direction the door member is forced open and upon operation of the lever in the reverse direction the door member is pulled to tightly closed position.

5. In an operating mechanism for a sliding door member associated with a frame member, the combination with a pair of abutment elements fixed to one of said members; of a toggle mechanism mounted on the other member, said toggle mechanism including a lever having a fulcrum member thereon adapted to be detachably connected with said abutment elements; and guiding means associated with said abutment means and coacting with said fulcrum member.

6. In an operating and locking mechanism for a sliding door member associated with a frame member having a door opening therein, the combination with an element having a pair of abutment faces thereon, said element being mounted on one of said members; of a toggle mechanism mounted on the other member, said toggle mechanism including a lever having fulcrum means at one end thereof adapted in one position of the lever to be engaged between said abutment elements to hold the door tightly closed, said lever and element being also provided with additional interengaging means adapted to cooperate in another position of the lever to hold the door partly opened; and locking means for retaining the lever in either of said positions.

7. In an operating mechanism for a sliding door member, associated with a frame member, the combination with an abutment element fixed to one of said members; of a holding lug on said element, said lug having an inclined guide face thereon; a link pivoted on the other member; an operating lever for the link, said operating lever having fulcrum means thereon adapted to detachably engage with said lug; and means for temporarily supporting said lever with the fulcrum element thereof positioned to engage said inclined face, while the door is being closed, and to be guided thereby for engagement behind said lug.

8. In an operating and locking mecha-

nism for a sliding door member associated with a frame member having a door opening therein, the combination with a bracket fixed to one of said members, said bracket having a pocket formed therein and said pocket being open at the bottom; of abutment means on said bracket; operating lever mechanism connected to the other member and having abutment means thereon adapted to engage with said first named abutment means when the lever is disposed within said pocket, thereby preventing longitudinal movement of the lever; and a latch plate for closing the bottom opening of said pocket to confine said lever and thereby lock the door in position.

9. In an operating and locking mechanism for a sliding door member associated with a frame member having a door opening therein, the combination with a bracket fixed to one of said members and having a pocket therein, said pocket being open at the bottom; of an operating lever mechanism connected to the other member and adapted to be entered into said pocket in horizontal position, said lever and bracket having inter-engaging means thereon for holding the lever in two different positions when in said pocket to retain the door either in fully closed or partly opened position; and a latch plate for closing the bottom opening of said pocket to confine said lever therein and thereby lock the door in either of said positions.

10. In an operating and locking mechanism for a sliding door, the combination with an abutment member; of toggle means adapted to be detachably connected with said abutment for operating the door, said means including a hand operating lever; and means for locking said lever to said abutment to hold the door in closed position.

11. In an operating and locking mechanism for a sliding door, the combination with an abutment member; of toggle means adapted to be detachably connected with said abutment member for operating the door, said means including an operating lever; and cooperating means on said lever and abutment for locking said door in two different positions.

12. In an operating mechanism for a sliding door member associated with a frame member, the combination with an abutment element fixed to one of said members; of toggle means mounted on the other member, said toggle means including a link and an operating lever bodily movable with said link, said operating lever having means thereon for detachably connecting the same to said abutment element.

13. In an operating mechanism for a sliding door member associated with a frame member having a door opening therein, the combination with a bracket fixed to one of

said members having abutment means thereon; of toggle means bodily swiveled on the other member and adapted to assume a pendant position under the influence of gravity, said means including a link and a lever; and a fulcrum element on said lever adapted to be detachably engaged with the abutment means of said bracket, whereby upon operation of said lever in one direction the door member is forced open and upon operation of said lever in the reverse direction, the door member is pulled tightly closed.

14. In an operating mechanism for a sliding door member associated with a frame member, the combination with a pair of abutment elements fixed to one of said members; of a toggle mechanism mounted on the other member, said toggle mechanism including a lever having a fulcrum member thereon adapted to be detachably connected with said abutment elements, said fulcrum element being brought into forcible engagement with one of said elements upon movement thereof in one direction to pull the door closed and adapted to be brought into forcible engagement with the other abutment element upon reverse movement of the lever to effect an opening movement of said door.

15. In an operating mechanism for a sliding door member associated with a frame member, the combination with a pair of abutment elements fixed to one of said mem-

bers; of a toggle mechanism mounted on the other member, said toggle mechanism including a lever having a fulcrum member thereon adapted to be detachably connected with said abutment elements, said fulcrum element being brought into forcible engagement with one of said elements upon movement thereof in one direction to pull the door closed and adapted to be brought into forcible engagement with the other abutment element upon reverse movement of the lever to effect an opening movement of said door member; and means for locking said lever in position to hold the door tightly closed.

16. In an operating and locking mechanism for a sliding door member associated with a frame member having a door opening therein, the combination with a pair of abutment elements fixed to one of said members; of a toggle mechanism mounted on the other member, said toggle mechanism including a lever having fulcrum means at one end thereof adapted in one position of the lever to be engaged between said abutment elements to hold the door member in tightly closed position; and locking means for retaining the lever in said position.

In witness that I claim the foregoing I have hereunto subscribed my name this 4th day of December 1923.

STACY B. HASELTINE.
